United States Patent Office

Des. 196,596
Patented Oct. 15, 1963

196,596

BEAN BAG

T. Morgan Carr, 83 Plymouth Ave., Swampscott, Mass.

Filed Mar. 4, 1963, Ser. No. 73,797

Term of patent 14 years

(Cl. D34—15)

FIG. 1

FIG. 2

FIGURE 2 is a view of the other side of the bean bag; and

I claim:

The ornamental design for a bean bag, as shown.
